United States Patent

Des. 242,255

Patented Nov. 9, 1976

242,255

DEEP TEXTURED DECORATIVE LAMINATE SHEET

Jack August Willard, Hamilton, and Robert Edward Schmitt, Cincinnati, Ohio, assignors to Formica Corporation, Cincinnati, Ohio

Continuation of abandoned design application Ser. No. 23,626, June 23, 1970. This application Sept. 6, 1972, Ser. No. 286,794

Term of patent 14 years

Int. Cl. D25—01

U.S. Cl. D25—84

The figure is a plan view of a deep textured decorative laminate sheet showing our new design, the sheet being of conventional thickness.

The application is a continuation of our copending application, Ser. No. D. 23,626, filed June 23, 1970, and now abandoned.

We claim:

The ornamental design for a deep textured decorative laminate sheet, substantially as shown.

References Cited

Sweet's Architectural Catalog File, 1965, section 4c/Bu, p. 1, slate panel illustration.

Sweet's Architectural Catalog File, 1962, section 13f/Bu, p. 2, select grade irregular flagging at top right.

Sweet's Architectural Catalog File, 1970, section 3c/Un, p. 2, pattern No. 4, converted lines.

A. HUGO WORD, Primary Examiner